UNITED STATES PATENT OFFICE.

CHARLES D. PLYMPTON, OF NEEDLES, CALIFORNIA.

WINDMILL.

No. 856,364.

Specification of Letters Patent.

Patented June 11, 1907.

Application filed November 28, 1906. Serial No. 289,397.

To all whom it may concern:

Be it known that I, CHARLES D. PLYMPTON, a citizen of the United States, residing at Needles, in the county of San Bernardino, State of California, have invented certain new and useful Improvements in Windmills; and I do hereby declare the following to be a full, clear, and exact description of the invention, such as will enable others skilled in the art to which it appertains to make and use the same.

This invention relates to wind mills.

One object is to provide a wind mill embodying such characteristics as to utilize the variety and quantity of natural air currents in the propulsion and operation of the mill.

Another object resides in the provision of a wind mill constructed and arranged to present its wings automatically in the direction of the wind and thereby create power for use at distant points and for the pumping of water from wells.

With these and other objects in view, the present invention consists in the combination and arrangement of parts as will be hereinafter more fully described, shown in the accompanying drawings and particularly pointed out in the appended claims, it being understood that changes in the form, proportion, size and minor details may be made, within the scope of the claims, without departing from the spirit or sacrificing any of the advantages of the invention.

In the drawings: Figure 1 is a side elevation of my invention partly in section. Fig. 2 is a top plan view. Fig. 3 is a detail view of the operating lever and the plate upon which it is pivoted. Fig. 4 is a detail view of a latch.

Referring now more particularly to the accompanying drawings, the reference character 1 designates a base block provided with a perforation 2 in which is fitted a casing 3 provided with an upper peripheral flange 4 designed to engage with the top of the base block 1 to support the casing therein.

The reference character 5 designates an inverted U-shaped frame whose legs 6 are provided with feet 7 by which the frame may be set up. The bight portion 8 of the U-shaped frame is provided with a perforation 9 designed to aline with the aforesaid perforation 2 of the base block 1 and in this perforation of the bight portion of the frame 5 there is fitted a bushing 10.

Fitted through the perforations 2 and 9

and the sleeve 3 and bushing 10 is arranged a rotatable shaft 11 which depends mainly for its support upon the base block 1. This shaft 11 adjacent the bushing 10 is provided with a groove 12 surrounding which is a sleeve 13 for a purpose presently explained.

Upper and lower collars 14 and 15 are secured to the shaft 11 in spaced relation with respect to each other and upon the upper faces of each of these collars there is disposed a series of radiating arms 16 and 17 respectively. Bridging these upper and lower arms at the outer extremities thereof are pairs of wings 18. It will thus be understood that there is but one pair of wings connecting each alining upper and lower radiating arms 16 and 17 and reference to the drawings will disclose that these wings are hingedly connected to the respective upper and lower arms by means of suitable hinges 19 so that they may spring outwardly from the arms when turned in the direction of the wind or lie close thereto when being carried in the same direction in which the wind is blowing. It might be remarked that these upper and lower radiating arms 16 and 17 are braced by means of suitable bolts 20 and that the arms are prevented from sagging by reason of tie rods 21 secured to the upper arms and to a plate 22 secured upon the upper end of the vertical shaft 11.

When the wings 18 are traveling in the direction of the wind and are consequently thrown back into engagement with the radiating arms 16 and 17, they are automatically locked against the latter by means of suitable catches 23, there being two of these catches pivoted intermediate their ends by means of a suitable pivot pin 24 to each of the lower radiating arms 17. Each catch is provided with a hooked end 25 for engagement with the corresponding wing 18 and is held to normally throw its hook into engagement with the wings by reason of a spring 26 secured to one end thereof and to the corresponding radiating arms 17. These catches 23 are provided each with a perforation 27 adjacent its pivot through which is passed a wire 28, which wire 28 passes over a sheave 29 secured to the under face of the corresponding lower radiating arm 17 and is connected in any suitable manner to the flange portion 30 of a sleeve 31 mounted to slide longitudinally of the shaft 11. Connecting this sleeve 31 is another wire 32 leading downwardly through the aforesaid groove in-

closed by the sleeve 13 for connection with a link 33 having one end pivotally connected to the projection 34 of a hand lever 35 pivoted in any suitable manner at its inner end to a plate 36 secured upon the vertical shaft 11 intermediate the base block 1 and the bight portion of the frame 5. When this lever 35 is thrown outwardly of the catch 37 of the plate 36 the catches 23 are so disposed as to 10 lock the wings 18 against outward swinging movement and consequently in order to release the wings 18 from engagement with the catches 23 so that the wings may swing outwardly of the radiating arms, it is simply necessary to force the lever 35 downwardly into 15 engagement with the catch 37.

From the foregoing, it will be understood that the wind mill may be readily thrown into and out of operation and that it may be 20 quickly put into operation by manipulating the lever 35 to release the wings 18 from engagement with the catches 23.

Mounted upon the vertical shaft 11 immediately above the sleeve 3 is a collar 38 about 25 which may be secured a belt or the like (not shown) for the transmission of power to distant points. The upper end of this collar 38 is provided with teeth 39 through the instrumentality of which power may be transmitted 30 to a distant point in a manner well understood. The lower extremity of the vertical shaft 11 is provided with a disk 40 which is secured thereto in any suitable manner and which performs the function of a crank to 35 which may be secured a crank pin 41 for connection with a pump rod in a manner well understood for the lifting of water from a well.

In order to limit the outward swinging 40 movement of the several pairs of wings, a pair of stops 42 is secured to each arm 16, as shown in Fig. 2. These stops are disposed upon the arms at right angles thereto, and extend laterally therefrom in the direction 45 opposite to that in which the shaft 11 rotates. When the wind, therefore, blows in the direction indicated by the arrow in Fig. 2, and the shaft is rotated counterclockwise, the wings will be held close against the sides of 50 the arms until each arm passes the dead center line (so to speak) when the wings will be free to move outwardly under the pressure of the wind, into contact with the stops, as indicated by the reference numeral 42' in said figure.

What is claimed is:

1. A windmill comprising a frame and a

base block, a vertical shaft journaled in the frame and base block, upper and lower collars arranged in spaced relation upon the 60 shaft above the frame, radiating arms secured to each of the collars, a pair of wings hingedly connected to the outer ends of said arms, a pair of spring-actuated catches pivotally mounted upon each of the lower radiating 65 arms for engagement with the corresponding wings of the latter to hold the same against swinging movement, a sheave secured to each of said lower arms, a collar slidably mounted upon said shaft below said 70 lower arms, a flexible connection between each of said catches and said last mentioned collar, said connections each passing over the corresponding sheave, and means for moving said sleeve to simultaneously release all of 75 said catches from engagement with said wings.

2. A wind mill comprising a base block and a frame, a vertical shaft journaled in the base block and frame, upper and lower radiating 80 arms secured to the shaft above the frame, a pair of wings hingedly connected to the outer end of the respective upper and lower arms, bolts between the corresponding upper and lower arms for bracing them, a plate secured 85 to the upper end of the vertical shaft, tie rods connecting the said plate to the upper radiating arms, the aforesaid shaft having a groove in one of its sides, a sleeve embracing the shaft adjacent said groove, a second 90 sleeve mounted for sliding movement above the first named sleeve, a pair of spring actuated catches pivotally secured upon each of the lower radiating arms for engagement with the corresponding wings of the latter to 95 lock the wings against swinging movement, a sheave mounted upon each of the lower arms, a connection between the respective pairs of catches and the said slidale sleeve, the corresponding connections passing over 100 the corresponding sheaves, a lever pivotally mounted upon the vertical shaft, and a connection between the lever and the slidale sleeve for moving the latter, the last named connection passing inwardly of the first 105 named sleeve and lying in the groove of the shaft, and means secured upon the shaft for transmitting power to distant points.

In testimony whereof, I affix my signature, in presence of two witnesses.

CHARLES D. PLYMPTON.
